UNITED STATES PATENT OFFICE

EARL KENYON, OF KANSAS CITY, MISSOURI, ASSIGNOR TO THE LONG-BELL LUMBER COMPANY, OF KANSAS CITY, MISSOURI, A CORPORATION OF MISSOURI

DOOR AND THE LIKE

Application filed September 9, 1927. Serial No. 212,375.

This invention relates generally to doors, windows and the like, and one of its objects is to provide a convenient way of changing a door or window to suit it to different seasons or purposes without having to substitute an entire door or main sash frame of the window for another.

In order to explain the invention to the best advantage, an embodiment of the ideas in a combination storm and screen door is illustrated in the accompanying drawings and is hereinafter described in detail. As will be clear later, the invention comprises a main frame such as a door, and a plurality of interchangeable sashes any desired one of which may be fastened in position in the main frame. In a set of the sashes, one may carry wire screen, another panes of glass and another solid panels so that the door may be made to serve several purposes without having to make a change in the main frame. Another object of the invention is to provide a construction whereby this interchange of sashes may easily be effected and the sashes fastened in position in the main frame in such a way that they will not rattle.

Still another object is to provide a construction for fastening the sashes in the main frame which does not include exposed catches or other disfiguring elements, and which will not interfere with dressing down the frame in fitting it in position.

Still another object of the invention is to provide a construction having the advantages previously stated which can be manufactured at a minimum cost.

With the foregoing and other objects in view, the invention consists in a novel construction and combination of parts, the novel features of which are pointed out in appended claims, and an illustrative embodiment of which is hereinafter described with references to the drawings accompanying and forming a part of this specification.

45 In said drawings:

Fig. 1 is a front elevation of a door having one of the set of sashes fastened in position.

Fig. 2 is a section on the line 2—2 of Fig. 1.

50 Figs. 3 and 3^a are sections corresponding

to Fig. 2, and show respectively wire screen and glass in the inter-changeable sashes.

Fig. 4 is a section on the line 4—4 of Fig. 1.

Figs. 5 and 6 are different views of some of the features of the mechanism for fastening the interchangeable sashes in position.

Fig. 7 shows in perspective the construction of the lower part of the main frame of the door and a similar view of the corresponding part of one of the interchangeable sashes.

The construction illustrated in the drawings comprises a main door frame 10 and the three sashes 11, 12 and 13 shown respectively in Figs. 2, 3 and 3^a. In each instance the details of how the door and sashes are built up or put together are either omitted or are shown in a more or less conventional form, as the exact way in which the various pieces making up the sashes or the main frame are put together is unimportant. For example, the paneling in the door shown in Figs. 1 and 2 is illustrated as being formed in or on a single sheet of material, whereas the usual construction would involve assembling together a number of panel and other pieces to get substantially the same appearance. Likewise the main frame 10 of the door and the interchangeable sashes 11, 12 and 13 are shown as being each a unit, whereas they may, as a matter of fact, be made up of the necessary pieces of material joined or fastened together in any of the usual ways.

The sashes 11, 12 and 13 are all of the same outside dimensions and have all of their corresponding edges formed alike. This is so that they will be interchangeable one for another in the main frame 10 of the door and fit equally well when in position. The sash 11 is provided with a solid panel construction 14, the sash 12 with a wire screen 15 and the sash 13 with one or more panes of glass 16. After the main frame or door 10 is hung, any one of the sashes may be put in the frame, thereby making it possible to convert the door from an ordinary storm door to a glass door or a screen door as desired.

The main frame 10 is recessed in one of its faces, as shown at 17, to receive the sashes and the sashes are preferably each constructed on three of the edges to provide a rib or

shoulder 19 cooperating with the portion 20 of the recess so as to limit the movement of the sash in one direction with respect to the main frame.

The bottom of the main frame 10 is recessed on the rear side, as shown at 21, and each of the sashes 11, 12 and 13 has a rib or shoulder 22 along its lower edge shaped to cooperate closely with the recessed or cut away portion 21. In inserting one of the sashes, when making a change, the lower edge of the sash is inserted through the bottom of the opening 23 (Fig. 1) in the main frame so as to cause the rib 22 to engage with the lower recess 21 on the rear of the frame when the upper part of the sash is pressed into position in the recessed portion 17 in the face of the frame. The construction is such that when the sash is fully in position the rib 22 will, because of the cooperation of the engaging parts of the side shoulders 19 and portions 20, be drawn into close engagement with the face 24, thereby holding the lower part of the sash firmly in position with respect to the main frame 10. After the sash is fully seated in the recess in the frame 10, it is held in that position by means which will next be described.

Near the top of the main frame 10 are two tubular holes 25 (Figs. 1, 5 and 6) extending inward from the edges of and through the sides of the frame 10. The corresponding portions of each of the inter-changeable sashes are provided with slots 26 which are slightly narrower than the diameters of the holes 25 and rods 27. The rods 27 and holes 25 are of about the same diameter and each rod has a screw thread 28 on its periphery extending only far enough, as compared with the length of the rod, to give a firm engagement with the interior of the hole 25. Each rod has its outer end formed to cooperate with a suitable wrench or screw-driver, the latter being preferred. In the drawing the rods are shown as having slots across their outer ends.

When the rods 27 are driven into their fastening positions, their inner ends will engage the slots 26 in the sashes and hold the sashes in position. As previously stated, the slots in the sashes are slightly narrower than the diameters of the rods 27 so as to insure firm engagement of the rods with the slots to prevent rattling of the sashes. The slots 26 may also be so positioned that when the rods 27 are forced home there will be a pronounced tendency to force the sash more firmly into engagement with the seat of the recess in the main frame 10. These fixtures all cooperate with the others previously mentioned to hold the sash firmly in place with respect to the main frame so as to prevent rattling or vibration of the sash.

As shown in Figs. 1 and 5, the rods 27, when in sash holding position, are counter-sunk,

i. e., their outer ends are at some distance from the edges of the frame 10. This permits dressing down the edges of the door when fitting it in position without striking the rod or causing the end of the rod to protrude after such dressing.

The threads 28 on the rods 27 are preferably of the fast type, that is, it takes comparatively few turns of the rod to give the desired endwise movement of the rod in either direction. This aids in quickness and convenience in assembling the parts or making an exchange of sashes. Quickness and convenience are also furthered by the fact that the threads 28 have only a few turns, as in putting the rods in place a large part of their endwise movement can be effected before the threads come into play and, of course, the reverse is true when the rods are removed.

In describing the construction illustrated in the drawings it was necessary to use the words front and back, also such words as top, sides, bottom and the like, when referring to various parts of that construction. This was done, however, simply as a matter of convenience, and the use of the terms mentioned is not to be construed as imposing limitations. The invention can obviously be embodied in forms as to which such terms would not be applicable.

In fact, while the construction shown and described in detail is admirably adapted to fulfill the purposes primarily stated, the inventive ideas are capable of various embodiments, with suitable modifications and changes, all coming within the scope of the claims which follow.

What is claimed is:

1. In a device of the character described, a set of interchangeable sashes each having a ledge or rib projecting from one edge thereof, a main frame recessed in one side to receive the sashes and cut away on the opposite side to receive the rib on each of the sashes, and removable rods threaded for a part of their lengths counter-sunk in the edges of the main frame and engaging recesses in the edges of the inserted sash, said rods being slotted in their outer ends for engagement by a screw-driver.

2. In a device of the character described, a set of interchangeable sashes each having a rib at its lower rear edge, a main frame recessed in the outer side to receive the sashes and cut away in its opposite side at the bottom of the recess to receive the ribs on the sashes, and removable threaded rods counter-sunk in the edges of the main frame and engaging recesses in the edges of the inserted sash at points distant from the rib on the sash to hold the sash in the main frame, said rods being slotted in their outer ends for engagement by a screw-driver.

3. In a device of the character described, a set of interchangeable sashes each having a

rib at its lower rear edge, a main frame recessed in one side to receive the sashes and cut away on its opposite side at the bottom of the recess to receive the rib on each of the sashes, and removable threaded rods engaging holes in the edges of the main frame and recesses in the edges of the interchangeable sashes to hold the inserted sash in position.

4. In a device of the character described, a set of interchangeable frames each supporting screens or the like and having a rib at its lower rear edge and a rib at its upper front edge, a main frame recessed at one side to receive the interchangeable frames and cut away at the top and bottom of the recess to receive the ribs on the interchangeable frames, and removable threaded rods engaging holes in the edges of the main frame and slots in the edges of the interchangeable frames to hold said latter frames in position in the main frame, said slots being narrower than the diameters of the rods, the ends of the rods and the slots cooperating to firmly seat and hold the interchangeable sash in the recess therefor.

In testimony whereof I hereto affix my signature.

EARL KENYON.
